UNITED STATES PATENT OFFICE.

HENRY HENDERSON, OF SCOTCH PLAINS, NEW JERSEY, AND WILSON D. CRAIG WRIGHT, OF PHILADELPHIA, PENNSYLVANIA.

WINDOW-OPERATING DEVICE.

1,125,817.

Specification of Letters Patent. Patented Jan. 19, 1915.

Application filed April 4, 1914. Serial No. 829,477.

To all whom it may concern:

Be it known that we, HENRY HENDERSON and WILSON D. CRAIG WRIGHT, citizens of the United States, residing, respectively, at Scotch Plains, in the county of Union and State of New Jersey, and at Philadelphia, county of Philadelphia, and State of Pennsylvania, have invented certain new and useful Improvements in Window-Operating Devices; and we do hereby declare the following to be a full, clear, and exact description of the invention, such as will enable others skilled in the art to which it appertains to make and use the same, reference being had to the accompanying drawings, and to characters of reference marked thereon, which form a part of this specification.

The present invention has reference, generally, to improvements in window operating devices; and, the invention relates more particularly to a novel and simple construction of mechanism adapted to be connected with a window whereby the same is properly balanced, and by means of which the window may easily and quickly be raised or lowered by a simple operation requiring little effort or muscular exertion.

The invention has for its principal object to provide a novel and properly balanced opening and closing mechanism for connection with any type of window, but more particularly adapted for use with the windows and doors of limousine auto bodies, coaches, railway carriages and similar vehicles. To this end the present invention provides a lazy-tongs mechanism in connection with which is an adjustable balancing mechanism whereby the weight of the window, as connected with said lazy-tongs device, is properly balanced to render its movement up or down easily accomplished by the application of but a comparatively slight force, and, furthermore, we provide a novel means for producing the extending or contracting movements of said lazy-tongs device, whereby a smooth, positive and easily applied operating force may be exerted thereon, to cause the closing and opening movements of the window, the small amount of primary movement of the operating parts

being multiplied by the lazy-tongs device to complete the full closing or opening movement of said window.

Other objects of the present invention, not at this time more particularly enumerated, will be clearly understood from the following detailed description of the said invention.

The said invention consists, primarily, in the novel window opening and closing mechanism hereinafter set forth; and, furthermore, the invention consists in the several novel arrangements and combinations of the various parts of the same, as well as in the details of the construction thereof, all of which will be fully described in the following specification, and then embodied in the appended claims.

The invention is clearly illustrated in the accompanying drawing, in which:—The representation is that of an elevation of said window opening and closing mechanism, a portion of the inclosing frame-work of the body or door in which it is mounted being removed to show the same, and the mechanism being shown operated to close the window-member.

Referring now to the said drawings the reference character 1 indicates the body of the window or door frame provided with the opposite vertical grooves or channels 2 in which is slidably disposed the glass window-member 3, so that the latter is vertically movable therein. The reference character 4 indicates a cross-piece which forms a part of the frame-work of said window or door-frame 1. Secured within the interior space 5 at the lower end of said window or door-frame is a fixed vertical standard 6, the upper end of which is secured to said cross-piece 4, and the lower end of which is secured to the bottom cross-piece 7 of said window or door frame. Connected with the lower end of said vertical standard 6 are a pair of oppositely extending horizontal arms 8, each being provided with a slot or elongated opening 9.

The reference-character 10 indicates a lazy-tongs device, the free ends of the lower member 11 of which are provided with jour-

nal-pins 12, upon which are journaled grooved rollers 13 which respectively pass through and ride in said slots or elongated openings 9 of said horizontal arms 8.

- 5 The reference character 19 indicates a shaft, one end of which is journaled in the upper end of said vertical standard 6, and the opposite end of which extends outwardly through the inner face of said door 10 or window-frame. Secured upon the inner end of said shaft 19 is a pinion or spur-gear 22. Mounted to move vertically in a guide-member 23, which is secured to the upper end of said vertical standard 6 is a rack 24 10 the teeth of which mesh with said pinion or spur-gear 22. The lower end of said rack 24 is secured in a socket-piece 25 from the lower end of which depends a perforated ear or lug 26. Pivots connected with said 15 ear or lug 26 is the upper end of a connecting-link 27, the lower end of which is pivotally connected with the pivot-pin 28 by means of which the two lower members 11 of said lazy-tongs device are joined together. 20 Said vertical standard 6 is provided with a vertical slot 29 through which said pivot-pin extends to its connection with said lower end of said connecting-link 27, and in which the same rides during the extending and 25 collapsing movements of said lazy-tongs device. Secured upon the outer end of said shaft 19 is a suitable handle-member for rotating said shaft and its gear 22.

Connected with the vertical standard 6 30 are a pair of oppositely extending bracket-arms 41, each being provided at its outer end with a perforated ear or lug 42. The said link 27 is provided with a cross-bar 43 rigidly secured thereto, the outer ends of 35 which are provided with perforated ears or lugs 44, into which are hooked the lower ends of counter-balancing springs 45, the upper ends of said springs being connected with screw-threaded adjusting members 46 40 which pass through the perforated ears or lugs 42 of said bracket arms 41, and are adjustably suspended therefrom by means of the lock-nut devices 47. Since the link 27 is interconnected with said lazy-tongs device 45 and the cross-bar 43 with said link 27, it will be apparent that the tension or pull of said springs 45 by pulling upwardly upon the latter members will tend to extend 50 said lazy-tongs device, and in such manner 55 counter-balance the weight of the window 3.

The carrier-bar 17 of the window 3 is provided with the slotted runways 48, and the upper members 14 of said lazy-tongs device 10 are provided with rollers 49 which 60 ride in said slotted runways during the movements of said lazy-tongs device and operatively connect the latter with the window-member.

The manner of operating the novel win-

dow opening and closing mechanism is as follows:—When the handle-member upon said shaft 19 is rotated to cause the rotation of said shaft 19 and said spur-gear or pinion 22, the rotation of said pinion or spur-gear 22 is transmitted to said rack 24 which is thereupon caused to move downward, its downward movement being in turn transmitted to said connecting-link 27 and thereby to the lower members 11 of said lazy-tongs device 10, causing the latter to collapse, and thereby carry down in its guide 2 the window-member 3 to its fully opened position, or any desired intermediate open position. To raise the window the handle-member is rotated in the opposite direction thereby causing a reverse operation of the mechanism and a consequent extension of the lazy-tongs device 10, which raises upward the window-member 3.

Of course, it will be apparent that the comparatively small or short movement of the rack is multiplied by the action of the lazy-tongs device whereby the full distance of travel of the window-member is attained, consequently less than a complete rotation of said handle-member, shaft and pinion or spur-gear will produce the desired movement of the lazy-tongs device.

We are aware that some changes may be made in the various arrangements and combinations of the several devices and parts of our present invention without departing from the scope of the same as described in the foregoing specification, and as defined in the claims appended hereto. Hence, we do not limit our invention to the exact arrangements and combinations of the various devices and parts as herein set forth, and as illustrated in the accompanying drawings, nor do we confine ourselves to the exact details of the construction of the said parts.

We claim:—

1. A device for opening and closing windows by means of a lazy-tongs device operated by a rack and pinion, comprising a supporting means for said lazy-tongs device and said rack and pinion, a link interconnecting said rack with the pivot-pin of the lower members of said lazy-tongs device, means for guiding and anchoring the lower members of said lazy-tongs device, a cross-bar connected with said link, and window-balancing springs suspended from said supporting means and connected with said cross-bar.

2. A device for opening and closing windows by means of a lazy-tongs device operated by a rack and pinion, comprising a supporting means for said lazy-tongs device and said rack and pinion, a link interconnecting said rack with the pivot-pin of the lower members of said lazy-tongs de-

vice, means for guiding and anchoring the lower members of said lazy-tongs device, a cross-bar connected with said link, and window balancing springs suspended from said supporting means and connected with said cross-bar, and means for adjusting the tension of said balancing springs.

In testimony, that we claim the invention

set forth above we have hereunto set our hands this eleventh day of March, 1914. 10

HENRY HENDERSON.
WILSON D. CRAIG WRIGHT.
